UNITED STATES PATENT OFFICE.

GEORGE A. PARMENTER, OF CAMBRIDGE, MASSACHUSETTS.

LIFE-GUARD FOR AUTOMOBILES.

1,110,225.

Specification of Letters Patent.

Patented Sept. 8, 1914.

Application filed September 16, 1913. Serial No. 790,066.

To all whom it may concern:

Be it known that I, GEORGE A. PARMENTER, citizen of the United States, residing at Cambridge, Massachusetts, have invented 5 certain new and useful Improvements in Life-Guards for Automobiles, of which the following is a specification.

My present invention relates to improvements in fenders or life guards designed 10 more especially for use on automobiles.

In devising my present invention, I have aimed to provide an extremely simple and economical form of guard which may be readily applied to any of the ordinary types 15 of motor car.

Further objects which I have had in view are to provide a device which will yieldingly receive the impact of the body encountered without the disastrous rebound which usually takes place, and which may be folded 20 back out of the way for access to the front of the car for cranking or other purposes, or when running on rough country roads.

With these and other objects in view, the 25 invention includes the novel features of construction and arrangement and combination of parts hereinafter described and particularly pointed out in the appended claims.

An embodiment of the invention is illustrated in the accompanying drawing, in which—

Figure 1 is a side view of the front portion of a motor car with my improved guard applied thereto and showing the normal position 35 of the parts in full lines, the position assumed by the guard on impact with a body in dotted lines, and the folded back position in broken lines. Fig. 2 is a plan view, and Figs. 3 and 4 are detail views.

Referring by reference characters to this drawing, the numeral 1 designates the front portion of the body of a motor car, and 2 the springs. I find that a convenient manner of effecting the support of the guard is 45 by securing it to the front portion of the springs, and to this end I provide brackets 3, which are designed to be secured to the upper leaves of the springs by suitable clips. To these brackets are secured the bars 4, 50 from which bars the scoop or guard proper is supported.

My preferred manner of supporting this

scoop or guard is as follows: To the lower portion of each of the bars 4 is pivotally connected the rear end of a supporting rod 55 or member 5, which inclines downwardly to a point in suitable proximity to the road, the downward movement of the member 5 with relation to the supporting bar 4 being limited by a pin or lug 6. To the lower ends of 60 these members 5 the fender or guard proper is pivotally connected, the point of connection being indicated at 7. The fender comprises an upwardly extending frame comprising the side bars 8 and top cross member 65 8^a, and a forwardly extending front portion 9, 9^a, and between these two frames is secured a safety netting to catch a body encountered by the guard. I prefer to connect the netting directly to the frame 9, 9^a at 70 its lower edge, but to connect its side edges to flexible elements such as chains 10, the upper ends of which are elastically connected to the upper portion 8^a of the upwardly extending frame by springs 11. It is essential that the frame 8, 8^a should be capable of yielding backwardly under the impact of a body to prevent injury when it is desirable, and also extremely desirable that there should be no recoil or rebound to the frame, 75 as such rebound tends to throw the object out of or away from the fender, with the liability of resultant injury. The backward yielding of the fender is permitted by the pivotal connection at 7, and the springs or 80 elastic elements 12, preferably of curved leaf form extending from the uprights 8 back to the upper ends of the bars 4 and being substantially parallel with the rods or members 5. The connections between the springs 12 and the uprights 8 and bars 4 respectively 85 are pivotal connections. If a body be encountered by the fender, the springs 12 will yield and allow the fender to swing back a distance according to the force of the impact such, for example, as indicated in dotted lines, and to prevent the recoil or rebound of the fender under the action of the springs 12, I provide the ratchet bars 13 which are 90 pivotally connected at their forward ends to the uprights 8 preferably by the same device which connects the front ends of the springs 12. The rear ends of these ratchet bars are 95 provided with ratchet teeth 13^a adapted to 100

ride freely over a suitable pin or projection 13^b, so that as the ratchet bar moves rearwardly its teeth ride over and engage such projection, and prevent rebound or recoil 5 until released by hand.

- If it be desired to raise or lower the fender to bring its front edge a greater or less distance from the ground, it is only necessary to vary the inclination of the bars 4 by 10 loosening the nuts on the bolts which secure the bars 4 to the brackets 3, and after the adjustment has been effected, again tightening the nuts to clamp the bars together rigidly. In order to hold the bars more rigidly or firmly to the brackets after the nuts 15 on the bolts have been tightened the contacting faces of the lugs and bars may be roughened or serrated, as indicated respectively at 3^a and 4^a.
- 20 By reason of the pivotal connection at both ends of the inclined members 5 and springs 12, when it is desired to crank the car or if the fender is not needed or would be likely to interfere with the road 25 in rough country riding, it can be thrown backward over but free from the hood of the engine in the position indicated in broken lines. By holding the fender free from the engine hood when thus folded back scratching or defacing of the paint of the engine 30 hood is prevented.

Having thus described my invention what I claim is:

1. A fender or life guard for motor vehicles, comprising a pair of substantially upright bars, means for adjustably connecting said bars to the front end of a motor vehicle, supports projecting forward and downward from the lower ends of said bars, 35 40 a fender comprising a rigid substantially L-shaped frame pivotally mounted upon the front ends of said supports, a resilient connection between the upper portion of said fender frame and the upper ends of said bars, and locking means to prevent the rebound of the upper portion of the fender frame after it has been forced backwardly.

2. A life guard for motor vehicles comprising a pair of bars adapted to be adjustably connected to a motor vehicle, supporting members pivotally connected at their rear ends to the lower ends of said bars, and projecting forwardly and downwardly therefrom, a fender or scoop pivotally connected to the forward ends of said members, a pair of curved leaf springs pivotally connecting said fender above its point of pivotal support with the upper ends of said bars and a ratchet bar pivotally connected to the 50 55 60 portion of the fender above its point of pivotal support and co-operating with a suitable pin to hold the fender against rebound, substantially as described.

3. In combination with a motor vehicle, 65 a fender or scoop, a pair of links pivotally

connected at their rear ends with the motor vehicle, and at their front ends with the lower portion of the scoop, a second pair of links above and substantially parallel with the first named links and pivotally connected 70 respectively with the motor vehicle and with the fender, and rigid stop means for positively limiting the downward movement of the fender while permitting free upward folding movement thereof.

4. In combination with a motor vehicle, a fender or scoop, a pair of links pivotally connected respectively to the lower portion of the scoop and the front of the motor vehicle, a pair of links of resilient material 80 above and substantially parallel with said first named links, and pivotally connected respectively with the fender and the front of the motor vehicle, and a ratchet bar extending between the fender and a stationary 85 part on the motor vehicle, and operatively connected to said parts respectively, its points of connection being coincident with the points of pivotal connection of said resilient links whereby upward folding of the 90 fender is permitted without derangement of the connections.

5. In combination with a motor vehicle, a fender or scoop, a pair of substantially parallel elements pivotally connected at 95 their front ends with the scoop and at their rear ends with the vehicle, thereby permitting upward and rearward folding of the scoop, one of said elements being a resilient element, and means co-operating with one 100 of the elements for positively limiting the downward movement of the fender, substantially as described.

6. A life guard for motor vehicles comprising a pair of bars adapted to be adjustably connected to the front thereof, a pair of links pivotally connected at their rear ends with the lower ends of said bars, a fender or scoop pivotally connected to the front ends of said links, a pair of spring 110 links pivotally connected respectively to the fender and to the said bars above said first named links, and a pair of ratchet bars pivotally connected to the fender coincidently, with the pivots of the spring links, and having hooked ends engaging the pivots at the rear ends of said spring links, and ratchet teeth in proximity to said hooked ends.

7. In combination with a motor vehicle, a fender or guard, upper and lower sets of 115 links each pivotally connected respectively with the motor vehicle and the guard, the upper set of links consisting of curved leaf springs.

8. In combination with a motor vehicle, 12 upper and lower pairs of links pivotally connected at their rear ends with the motor vehicle and projecting forward beyond the same, a fender having a normally substantially upright portion pivotally connected 13

with the forward ends of said links, said links being of a length sufficient to permit the fender to be folded up and back with its normally upright portion extending 5 backward over and free from the engine hood, and means for normally holding the fender the desired distance from the ground.

In testimony whereof, I affix my signature in presence of two witnesses.

GEORGE A. PARMENTER.
